UNITED STATES PATENT OFFICE.

JOSEPH KRAUS, OF NEW YORK, N. Y.

CIGAR AND MOUTHPIECE THEREFOR.

SPECIFICATION forming part of Letters Patent No. 726,946, dated May 5, 1903.

Application filed June 12, 1902. Serial No. 111,231. (No model.)

To all whom it may concern:

Be it known that I, JOSEPH KRAUS, a citizen of the United States, and a resident of the city of New York, borough of Manhattan, and 5 State of New York, have invented a certain new and useful Cigar and Mouthpiece Therefor, of which the following is a specification.

My invention relates to improvements in the manufacture of cigars.

10 Prior to my invention cigars have been made with the filler or internal filling composed of "scrap-tobacco," as it is termed, which consists of comparatively small pieces of broken leaf. Cigars made of scrap-filler 15 have not been desirable mainly because the filler becomes loosened and enters the mouth of the smoker.

My invention has for its object to so construct a cigar that a scrap-filler may be used 20 without the usual attendant disadvantages and at the same time produce a new and improved combined cigar and mouthpiece.

My invention therefore consists in the novel construction and combination of parts here- 25 inafter described, and pointed out in the claims.

In the drawings forming part of this specification, Figure 1 is a side view of a cigar made in accordance with my invention; Fig. 30 2, an enlarged side elevation of a portion of the same with the interior wrapper removed; Fig. 3, an enlarged longitudinal section of the mouthpiece and a portion of the cigar, showing the securing strip or band for the cigar 35 and mouthpiece; Fig. 4, a like view with the securing-strip removed, and Fig. 5 a side elevation of the mouthpiece.

In making my cigar a bunch comprising the filler 1 and binder 2 is formed in the usual 40 or any desired way, the end or tip 3 of the bunch being cut off to expose the end of the filler. The filler may preferably be of scrap-tobacco, or, so far as some features of my invention are concerned, may be of long leaf 45 or leaf of varying sizes. The mouthpiece is formed of a tubular portion 4, preferably a hollow quill, with the end turned over, as at 5, to provide a grip or stop, and to the other end a conical holder 6 is secured by extending the end 7 of the tube into the top or narrowed portion 8 of the holder and firmly se-

curing them together by adhesive material. Any other form of holder can be used, providing, of course, it has a suitable mouthpiece and receiving portion for the bunch. The 55 tip end 9 of the bunch is then inserted into the holder 6, preferably extending the same so that the open portion 3 is in close contact with the end 7 of the tube 4, as shown in Fig. 4.

To firmly secure the holder and bunch together, I secure a strip 10 of suitable material; preferably a piece of tobacco-leaf, because that will not affect the flavor of the cigar, over the end of the holder and over the surface of the bunch or binder 2, which extends from the holder, the gum usually employed by cigar-makers being preferably employed for this purpose. This firmly secures the bunch and holder together, and the smallness of the tube 4 relative to the volume of 60 filler, as shown in Figs. 3 and 4, sufficiently prevents any of the filler from entering the tube, and should any of the finer particles of filler free themselves the tube being small and compressible while in use will effectu- 65 ally prevent such particles from entering the mouth of the user. The cigar is next finished by applying an exterior wrapper, preferably of tobacco-leaf, as 11, so as to cover the bunch, the strip 10, the holder 6, and a portion of the 70 tube 4. For this purpose the wrapper may be of any desired shape; but I prefer the usual strip or band wrapper, as shown in Fig. 1, which is cut in the usual way, tucked in at the butt 12, and rolled about the bunch over the 75 holder 6 and part of the tube 4 in the usual way, its tip 13 being secured by gum, thus finishing the cigar, binding the holder which then forms part of the cigar, and leaving but a comparatively small portion of the tube ex- 80 posed.

The entire cigar and the means for securing it to the holder can be consumed right up to the holder 6.

From the foregoing it will be clear that my 95 invention may be variously modified without departing from the spirit thereof.

I claim—

1. An article of the class described, comprising a cigar having a bunch consisting of 100 a filler and binder, a mouthpiece into which the bunch is inserted, a wrapper and means

comprising a sheet of material independent of said wrapper securing the bunch to the mouthpiece.

2. An article of the class described, comprising a cigar having a bunch, a mouthpiece into which the bunch is inserted, a wrapper, and a tobacco-strip independent of said wrapper securing the bunch to the mouthpiece.

10 3. An article of the class described, comprising a cigar having a bunch, a mouthpiece into which the bunch is inserted, a wrapper overlapping said mouthpiece, and fastened thereto, and a strip independent of said wrap-
15 per for securing the bunch to the mouthpiece.

4. A cigar comprising a bunch having an open end, a mouthpiece having a holder in which said open end is inserted, a strip cov-
20 ering the holder and adjacent part of the bunch, and a wrapper disposed over the bunch and holder.

5. A cigar comprising a bunch having a "scrap-filler" and an open end, combined
25 with a mouthpiece comprising a holder receiv-
ing the open end and a tubular extension in line with and adjacent said open end, a strip of tobacco-leaf encircling a part of the bunch and holder, and an exterior wrapper for the
30 bunch extending over the shoulder.

6. A cigar comprising a bunch having a "scrap-filler," a binder, and an open end,

combined with a mouthpiece comprising a holder receiving the open end and a tubular extension in line with and adjacent said open 35 end, a strip of tobacco-leaf encircling a part of the bunch and holder, and a wrapper of tobacco-leaf encircling the bunch, strip and holder.

7. A cigar comprising a bunch having a 40 "scrap-filler," a binder, and an open end, combined with a mouthpiece comprising a holder receiving the open end and a tubular extension in line with and adjacent said open end, a strip of tobacco-leaf encircling a part 45 of the bunch and holder, and a wrapper of tobacco spirally disposed about the bunch, the strip, the holder, and extending over a part of the tubular extension.

8. A mouthpiece comprising a compressible tubular part and a conical holder, combined with an open-end cigar-bunch inserted in the holder, a strip of tobacco laid over the adjacent portion of the bunch and holder, and a wrapper disposed over the bunch, the 55 strip, the holder, and a part of the tubular part for uniting them.

Signed in the city, county, and State of New York this 2d day of June, 1902.

JOSEPH KRAUS.
